UNITED STATES PATENT OFFICE.

ADOLPH A. THOMAS, OF NEW YORK, N. Y.

SOUND-REPRODUCING APPARATUS.

Application filed August 28, 1925. Serial No. 53,021.

My invention is for a new sound-reproducing device constructed as a combined phonographic and telephonic reproducer, which is adapted to be attached as a unit to a phonograph tone arm. This novel unitary mechanism is capable of performing a double function: it operates mechanically as a phonograph sound box in playing records through a needle, and it also operates electromagnetically as a telephone receiver. Only one diaphragm need be used, and this diaphragm is preferably disconnected from the electromagnetic mechanism when the device is operated as a phonographic reproducer.

The reproducing instrument of my invention is particularly useful in combined radio-phonograph cabinets, where the phonograph horn is utilized as an amplifier for the telephone receiver of the radio set. In prior cabinets of that type, it has been necessary, in the absence of special provisions, to remove the sound box from the tone arm and insert a loudspeaking telephone receiver. That, of course, is objectionable, for it requires the alternate removal and replacement of the sound box and the receiver,—an annoying procedure that nobody likes. To overcome this objection, it has been proposed to connect a separate sound tube with the neck of the horn and attach the telephone receiver to the tube. The connection between the horn and the receiver tube requires a controlling valve operated from outside the cabinet. The installation of these additional parts necessitates changes in standardized phonograph designs and also increases the cost of the machine. Another expedient heretofore employed as a means to obviate the removal of the sound box when it is desired to connect the radio receiver with the horn, consists of a special construction of tone arm in which a branch tube is provided for attaching the receiver. This requires the discarding of types of tone arms that phonograph manufacturers have been using for years as their own standard designs. Also, two separate and distinct devices mounted on different parts of the same tone arm destroy the original neatness and simplicity of the machine, especially in well-known makes.

The foregoing and other objections and disadvantages in prior radio-phonograph cabinets are overcome by the double-acting reproducer of my invention, which can be

substituted on the tone arm for the ordinary sound boxes heretofore used. The tone arm will, therefore, have a single reproducer unit, as before, but this new unit performs the two-fold function of playing records and amplifying the radio reception through the tone arm and the horn.

The basic principle of my invention may be mechanically embodied in various ways, and I have shown several illustrative constructions in the accompanying drawings, in which

Fig. 1 represents, in axial cross-section, a radio-phonograph reproducer embodying my invention;

Fig. 2 is a transverse cross-section on line 2—2 of Fig. 1;

Fig. 3 is a cross-section on line 3—3 of Fig. 2, showing the relative arrangement of the magnetic pole pieces and the armature;

Fig. 4 is a cross-section on line 4—4 of Fig. 1, showing the means for holding the armature against turning during axial adjustment thereof;

Fig. 5 illustrates, in axial cross-section, a modified form of construction, the armature being connected to the diaphragm;

Fig. 6 is a cross-section on line 6—6 of Fig. 5, showing the automatic switch connections for the telephone coil in the reproducer;

Fig. 7 shows a tone arm provided with the radio-phonograph reproducer of Fig. 5, the reproducer being shown in record-playing position;

Fig. 8 is a plan view of Fig. 7, certain parts being in section for clearness;

Fig. 9 is cross-section on line 9—9 of Fig. 8;

Fig. 10 is a view similar to Fig. 5 (with certain parts broken away), but showing the connection between armature and diaphragm broken;

Fig. 11 illustrates a fragmentary detail of the cooperating means on the reproducer and the tone arm for automatically controlling the connections between the armature and the diaphragm as the reproducer is moved into and out of its rest position on the tone arm, this view showing the cooperating parts in separated position;

Fig. 12 is a view similar to Fig. 11, except that the cooperating parts just referred to are shown in engaging position to connect the armature with the diaphragm;

Fig. 13 is a plan view of the spring mem-

ber carried by the tone arm and shown in Figs. 11 and 12; and

Fig. 14 shows in cross-section another modification, in which the lever that actuates the diaphragm has a slot for controlling the connection with the armature.

Before describing the drawings in detail, I want to make it plain that I have purposely shown the figures on an exaggerated scale, so as to make the drawings as clear as possible. The parts are shown heavier and more spread out than is necessary in an actual device, which can be made of about the size of an ordinary phonographic reproducer, except for a somewhat wider casing to accommodate the electromagnetic mechanism, as will be better understood later on.

I shall first describe the construction of Figs. 1-4. The operative parts of the radio-phonograph reproducer are enclosed in a suitable non-magnetic casing C, which in this instance comprises a cylindrical cover 1 and a pair of end plates 2 and 3. These parts are separably secured together, as by screws 4 or otherwise. The inner end plate 3 is provided with a hub 5 adapted to fit over a tubular extension 6, which is part of a tone arm, as will subsequently be more fully explained. In casing C is mounted a vibratory diaphragm 7 held in position by any practical means. In Fig. 1 the cover 1 is provided with an annular flange or shoulder 8 for seating the diaphragm, and an adjustable screw-threaded ring 9 clamps the diaphragm tightly around the edge. The shoulder 8 may be cast integral with the cover, or it may be secured in place as a separate piece. As is usual in the mounting of phonograph diaphragms, one or more gaskets 10 of felt, rubber and the like, may be used for acoustically insulating the diaphragm from the metal of the casing.

The casing C is provided with a suitable bracket 11, shown in the form of a pair of spaced arms, between which is pivoted at 12 a lever 13 for operating the diaphragm 7. The outer end of lever 13 terminates in, or is rigidly connected to, a needle holder 14 adapted to receive phonograph needles for playing records. The inner end of lever 13 is fixed to the center of diaphragm 7, as shown at 15. The lever 13 extends through a slot 16 in the cover 1 of the casing.

The phonograph mechanism thus far described may be of any practical design, and may follow any one or more of the reproducers adopted by phonograph manufacturers as their standard type.

I shall now describe the electromagnetic mechanism in Figs. 1 and 2 for operating the diaphragm 7. In the cylindrical cover 1 is fixed a permanent steel magnet M of circular body form and terminating in a pair of polar limbs or extensions 17, one of which is a north pole and the other a south pole. The

magnet may be made of a solid bar of steel or it may be laminated. The body of magnet M is fixed to the cover by screws 18 or in any other practical way. Attention is called to the compact form and arrangement of the magnet for securing great length of metal in a comparatively small space. In permanent magnets it is advantageous to have as great a length as possible in order to maintain the magnetism constant for a long time. To the polar limbs 17 are secured pole pieces 19 by screws 20 or otherwise. The pole pieces are preferably of soft iron, solid or laminated, and terminate in polar faces 21 which form a circular airgap 22, as shown in Fig. 3. Between the polar limbs 17, which are substantially parallel, is arranged a coil K having a hollow center 23 in line with the circular airgap 22. The coil K not only fits snugly between the inner sides of the polar limbs 17, but rests on the pole pieces 19, and is thus firmly supported on and by the magnet itself, without the need of separate supporting means. If desired, a pair of retaining clips 24 may be fastened to the pole pieces 19 to engage the adjacent end of the coil and positively hold it against accidental displacement. The clips 24 have curved spring extensions 25, which are placed under tension when the coil is inserted, and these extensions grip the coil like a pair of spring jaws. Since the coil is held in place entirely by friction, it is easily inserted and removed.

A hollow boss 26 of non-magnetic material is suitably fixed to the cover 1, as by screws 27, so as to be in alignment with coil K. The boss 26 is screw-threaded inside, as shown at 28 in Fig. 1, and carries a nut 29 provided with a stem 30. This stem projects through a hole in the casing and terminates in a finger piece 31. The nut 29 has two or more radial holes in which are fixed retaining pins 32. Into the recess of nut 29 extends a swivel plug 33, which has an annular groove 34 arranged to receive the pins 32. In this way, the plug 33 is locked to the nut 26 so as to move axially therewith in either direction, yet the nut 26 is free to turn without rotating the plug. The nut 29 and plug 33 should be of non-magnetic material to prevent diverting magnetic lines of force from the pole pieces. In order to lock the plug 33 positively against any tendency to turn during rotary adjustment of nut 26, I provide the plug with a slotted arm 35 adapted to engage a pin 36 projecting from the fixed boss 26. The arm 35 rides up and down the pin 36 during axial movement of plug 33. Any other suitable means may be used to hold the swivel plug 33 against rotary movement without interfering with its axial adjustments by the nut 29.

An armature 37, shown as a round bar of iron, is attached to the inner end of plug 33

33 by means of a short leaf spring 38, which is rigidly secured at its ends in slots provided for that purpose in the adjacent ends of the plug and the armature. The spring 38 is arranged in a plane substantially parallel with that of diaphragm 7, so as to allow vibration of the armature toward and from the diaphragm. The material and dimensions of spring 38 are so chosen as to give it the required degree of resiliency. This is readily determined by the mechanic. The spring 38 normally holds the armature centrally of the circular airgap 22, or as nearly so as mechanical conditions permit. The polar faces 21 of the magnetic pole pieces 19 are preferably curved concentrically with the armature 37, in order to reduce the airgap between the polar faces and the armature to a minimum and yet leave sufficient space for the armature to vibrate at maximum amplitude without striking the pole pieces. The free or vibrating end of the armature has a flat extension 39, which may be formed integral with the armature or may be a separate piece attached thereto. The extension 39 is provided with a longitudinal slot 40 and a transverse slot 41, the two slots being open to each other as shown in Fig. 1. In the T-shaped slot 40—41 engages a pin or lug 42 on an arm 43 projecting from the lever 13. The arm 43 may be formed integral with lever 13, or it may consist of a separate piece rigidly attached to the lever at a point between the pivot 12 and the end 15. The pin 42 fits snugly in slot 40 so that there is no lost motion in the connection between the vibrating armature 37 and the diaphragm 7. At the same time, the pin 42 permits axial adjustment of the armature for a purpose that will presently be explained.

The coil K is supposed to be connected in a suitable circuit traversed by variable currents of audio frequency. For example, the coil may be connected with a radio set mounted in a radio-phonograph cabinet which is equipped with the reproducer of my invention, so that this device constitutes the loudspeaker of the radio set. The leads of coil K may be carried through the tone arm A and enclosed in casing C, so as to be wholly invisible. In Fig. 2, the ends 44 of the coil are connected to insulated binding posts 45 on the boss 26. Conductors 46 lead from binding posts 45 through the tone arm, and from there they run to a suitable place in the cabinet for connection with the radio set. The casing C may be provided with a recess 47 in cover 1 and end plate 3 to accommodate the conductors 46 and keep them out of the way of all moving parts.

The operation of the mechanism above described will now be clearly understood. With the parts as shown in Fig. 1, when variable currents pass through coil K, the

armature 37 vibrates in the airgap between the pole pieces 19, and these vibrations are always in a plane at right angles to the plane of diaphragm 7. Consequently, the diaphragm vibrates in unison with the armature through the connection represented in this instance by the lever 13, arm 43, pin 42, and extension 39. Attention is directed to the fact that the movements of the armature are transmitted to the diaphragm in amplified ratio, as follows: First, the pin 42 vibrates through a greater arc than that part of the armature which operates between the pole pieces 19. Second, the point 15 where the lever 13 is connected to the center of the diaphragm, has a greater amplitude of vibration than the pin 42, which is really a point on the lever 13 about midway of the pivot 12 and the vibrating end 15. Hence, the vibrations of armature 37 in the airgap 22 are doubly amplified before reaching the center of the diaphragm, which therefore produces tones of loudspeaker volume when amplified through the phonograph horn.

The transmission ratio between armature 37 and diaphragm 7 may be varied by adjusting the nut 29. By simply turning the thumb piece 31, the nut 29 is moved toward or away from the coil K, carrying with it the swivel plug 33 and armature 37. The connection 35—36 prevents turning of plug 33, so that rotary adjustment of nut 29 is accompanied by an axial adjustment of the armature. This means that the distance between the suspension point of the armature and the pole pieces 19 is varied, with consequent variation in the amplitude of vibration of the armature at its point of connection with lever 13. It will be clear from Fig. 1 that, if the armature is adjusted in a downward direction, the leverage between the point of suspension (which is somewhere along the free portion of spring 38) and the connecting pin 42 is decreased. The result is that the armature vibrations are increased in amplitude at the point 42 in a greater ratio than when the leverage is lengthened by moving the armature upwardly (as viewed in Fig. 1). The operator can thus easily control the loudness of the diaphragm vibrations by simply turning the button 31. The cover 1 may be marked with appropriate signs to indicate the "loud" and "soft" positions of button 31. If desired, the stem 30 may carry a small pointer moving over a suitable scale on the cover 1 or on a disk surrounding the stem.

In the particular construction of Fig. 1, the axial adjustment of armature 37 not only permits control of the transmission ratio between armature and diaphragm, but it also allows the armature to be operatively disconnected from the diaphragm. If the armature 37 is moved upwardly (as viewed in Fig. 1) until the pin 42 engages in the cross-

slot 41, the lever 13 is disconnected from the armature. The purpose of disconnecting the armature from the diaphragm is to allow the free operation of the diaphragm by means of 5 phonographic needles in the same way as if the electromagnetic mechanism were not present. If the armature were to remain connected with the lever 13 during the playing of a phonograph record, the armature 10 would impose an extra load upon the diaphragm and this load might be sufficient to so hamper the phonographic operation of the diaphragm as to interfere with the correct reproduction of the record. This objection 15 is entirely obviated by providing an easily separable connection between the armature and the diaphragm. If the reproducer is to be used as a telephone loudspeaker after a record has been played, the button 31 is 20 turned until the pin 42 engages the axial slot 40, whereupon the armature 37 is again operatively connected with the diaphragm 7.

In Figs. 5-13 is shown a modified form of 25 radio-phonographic producer in which the connection between the armature and the diaphragm is automatically controlled when the reproducer has swung into and out of record-playing position. Such parts as are common to Figs 1 and 5 I need not describe 30 again in detail. The casing of Figs. 5 and 10 is provided with a fixed boss 48 arranged in line with coil K, the same as boss 26 of Figs. 1 and 2. In the lower end of boss 48 is fixed a plug 49, to which is attached one end 35 of the armature-supporting spring 38. The lower end of armature 37 is provided with a flat extension 50 carrying a pin 51 on which is pivoted a link 52. The free end of link 52 is in the form of a hook-shaped head 53 provided 40 with a slot 54. The lever 13, which operates the diaphragm 7, has a lateral pin 55 arranged to engage in the slot 54 of link 52. The slot 54 is preferably widened at the bottom and slightly converges toward the 45 inner end, so that the pin is easily guided into the slot and makes a tight fit therein. The cover 1 has a hole in which is fitted a frictional bushing 56 held rigidly in place. Through this bushing extends a 50 slideable plug 57 provided with a pair of fixed collars 58 and 59. The collar 58 may simply be a nut screwed on the plug 57, but the collar 59 is a metal ring of good conducting material insulated from the plug 57 by an insulating 55 sleeve 60 (see Fig. 6). On the boss 48 are fixed two insulated spring arms 61 to which the end wires 62 of coil K are connected. The free ends of spring arms 61 are arranged to be engaged by the insulated collar 59 when 60 the plug 57 is pushed in, as shown in Figs. 5 and 6. The outer end of plug 57 has a small knob 63 by means of which the plug 57 may be pushed in or pulled out. This operation 65 may be performed manually, but it is preferably accomplished in an automatic way, as I

am about to describe. A thin rod or stiff wire 64 connects the inner end of plug 57 with the slotted head 53 of the pivoted link 52.

When the plug 57 is pushed in, as shown in Fig. 5, the link 52 hooks over the pin 55 and the armature 37 is operatively connected with the diaphragm 7. When the plug 57 is pulled out as shown in Fig. 10, the link 52 is disconnected from lever 13, so that the diaphragm may be used for playing records in the usual way without being hampered by the armature 37. The collars 58 and 59 constitute stops for the inner and outer movements of the plug 57. This plug fits so snugly in the fixed frictional bearing 56 that it is safely held in either of its operated positions. By referring to Fig. 5, it will be seen that, when the plug 57 is pushed in, the conducting ring 59 connects the switch arms 61 and thereby closes the circuit through the coil K. It is to be supposed, of course, that proper circuit connections lead to the switch arms 61 from the radio set in the cabinet or from whatever electric system is used. When the plug 57 is pulled out to disconnect the diaphragm from the armature, as shown in Fig. 10, the electric connection between the spring terminals 61 is broken. In other words, when the armature is connected to the diaphragm, the circuit of the coil is closed and the instrument is in condition to operate as a telephone loudspeaker. However, when the diaphragm is disconnected from the armature, as when the reproducer is used for playing phonograph records, the circuit through the coil is interrupted and it is impossible to cause vibration of the armature 37 unless the same is connected with the diaphragm 7. This automatic circuit-controlling feature is not necessary in the broader aspect of my invention and may be omitted without sacrificing any of the practical advantages of the double reproducer. In that event, the collar 59 could simply be a nut, like the collar 58. If the plug 57 is to be operated by hand, the knob 63 may be in the form of a button that is easily grasped by the fingers. However, if the operation of plug 57 is automatically controlled by the movements of the reproducer into and out of playing position, the knob 63 is so shaped as to cooperate properly with the spring piece 65 shown in Figs. 11, 12 and 13. The spring piece 65 consists of a flat spring having bifurcated ends 66 which overlap to form an opening 67, as shown in Figs. 8 and 13. The spring piece 65 is secured to an extension 68 properly arranged on the tone arm A (see Figs. 7 and 8). The reproducer is mounted on the free end of the curved extension 6, usually called a goose-neck, which is pivoted in the transverse bushing 69 fixed on the outer end of the tone arm proper, as shown in

Fig. 8. The dotted line 6' in this figure indicates the inner end of goose-neck 6.

Fig. 7 shows the reproducer in phonograph-playing position, with the plug 57 pulled out so as to disconnect the diaphragm from the armature as illustrated in Fig. 10. When the reproducer is swung back on the tone arm into the position indicated by the dotted outline R in Figs. 7 and 8, the oval 10 knob 63 strikes the spring fingers 66 of member 65, and the first result is that the plug 57 is pushed in until the collar 58 strikes the casing. However, as the weight of the descending reproducer continues to bear 15 down on the yieldable spring device 65, the knob 63 pushes the spring fingers 6 and 7 apart, longitudinally and laterally under certain conditions, and snaps through the enlarged opening thus formed, whereupon 20 the entire reproducer is supported on the stop extension 68, as may be seen from Figs. 7 and 12. With the plug 57 pushed in when the reproducer rests on the tone arm in swung-back position, the armature 37 is operatively connected with the diaphragm 25 through the link 52 (see Fig. 5). The reproducer is now in condition to operate as a telephone loudspeaker in whatever connections it may be used. Let us now suppose 30 that it is desired to swing the reproducer from its rest position into record-playing position. When the reproducer is first lifted from the position R in Figs. 7 and 8, the resilient fingers 66 hold the knob 63 35 within the spring 65 until the collar 59 strikes the inner end of the fixed bushing 56. Continued upward lifting of the reproducer forces the knob 65 through the spring fingers 66 and the reproducer is now free to 40 be swung over into record-playing position.

It must be understood that in the automatic shifting of the plug 57 by moving the reproducer into and out of record-playing position, the engagement of knob 63 with 45 spring member 65, as well as the separation of these parts, takes place almost instantaneously and without any thought or separate act on the part of the operator. The size and shape of knob 63 and spring member 65 are so designed 50 that the knob encounters sufficient resistance to operate the plug 57 either way, and yet the spring fingers 66 are sufficiently yieldable to allow passage of the knob with the application of but little extra force. In 55 fact, the momentum of the reproducer as it descends will automatically carry the knob 63 past the spring fingers 66 into the final position shown in Fig. 12. This, of course, does not occur until after the fingers 66 have 60 held up the knob sufficiently to push the plug 57 in. It is only when moving the reproducer from rest position into record-playing position that the operator need exert any additional force at all in moving the knob 63 65 out of the spring device 65.

Since the radio-phonograph reproducer of my invention is necessarily heavier than an ordinary sound box (except, perhaps a certain type of heavy sound box that uses two diaphragms), I provide means to counteract the weight of the reproducer on the record, if it is found that its normal weight is too great for the proper playing of a record. Referring to Figs. 8 and 9, the lateral hub 69 on tone arm A is formed with an annular flange 70 on which is screwed a cap 71 provided with an inturned annular shoulder 72. The goose neck 6, which extends through the opening formed by shoulder 72, is provided with a fixed 70 collar 73 having a series of holes 73'. The goose-neck is held pivoted on the tone arm by the collar 73 being retained between the shoulder 72 and the outer end 69' of hub 69, as shown in Fig. 8. In the annular chamber 74 is mounted a coil spring 75. One end of this spring is attached at 76 to the flange 70 of hub 69, and the other end 77 of the spring is inserted in one of the holes 73' in collar 73. The spring is so arranged that when the reproducer is swung into record-playing position, the spring coils are wound up. The tension thus produced in the spring tends to lift the reproducer off the record and thereby counterbalances 80 its normal weight in a predetermined degree. The effective tension of spring 75 can be regulated by inserting it into the desired hole 73' when the goose-neck is pushed into the hub 69. Other means may be provided for adjusting the counter-effect of the spring on the weight of the reproducer. When the reproducer is swung back on the tone arm into rest position, the spring tends to unwind and thus assists or facilitates the movement. 90

The construction of Fig. 14 differs from that of Figs. 5 and 10 in one detail only, and that is the means for making and breaking the connection between armature and diaphragm. On the pin 51 at the free end of armature 37 is pivoted a link 78 provided with a pin 79. The lever 13 is formed with a T-shaped slot consisting of an axial portion 80 and a transverse portion 81. The link 78, like the link 52 of Figs. 5 and 10, is connected to the slideable plug 57 through the rod or stiff wire 64. When the plug 57 is pushed in, the pin 79 snugly engages in the axial slot 80 and thereby connects 100 the armature with the diaphragm. When the plug is pulled out, the pin 79 is in alignment with the transverse slot 81, so that the operative connection between armature and diaphragm is broken. The plug 57 in Fig. 110 14 may be operated by hand, or it may be automatically controlled, like the knob 63 in Figs. 5-13. Otherwise, what has previously been said about the operation and advantages of the invention applies to the 115 120 125 130

modification of Fig. 14 without the need of repetition.

It will be understood from the foregoing description of several illustrative embodiments of my invention that I have produced a combined radio-phonograph reproducer in the form of a self-contained unit adapted to be mounted on a tone arm like an ordinary sound box. This unit may be used 10 for playing records in the usual way, and it may also be operated as a telephone loudspeaker for amplifying sound waves through the tone arm and the phonograph horn. The reproducer of my invention is 15 particularly useful in radio-phonograph cabinets where the phonograph horn is utilized to amplify the vibrations of the telephone receiver connected to the radio set in the cabinet. My double reproducer unit requires no separate extension for acoustic 20 connection with the horn, and does away with all changing back and forth of sound box and telephone receiver on the tone arm, as heretofore.

25 Although I have shown and described certain specific constructions, I want it clearly understood that I have done so in order to explain my invention to those skilled in the art by means of several illustrative embodiments, and not by way of restriction or limitation of the invention. Various changes and alterations will doubtless occur to the mechanic within the scope of the invention as defined in the appended 30 claims. Also, certain features of the electromagnetic mechanism may be used in a telephone instrument independently of any connection with a phonographic diaphragm.

What I claim as my invention is:

40 1. A combined phonograph reproducer and loudspeaking unit including a diaphragm, a needle arm permanently connected to said diaphragm for operating the same, electric means for actuating said 45 needle arm, said means having a vibratory member, and a controllable mechanical connection between said member and said needle arm.

50 2. A sound reproducer adapted to be mounted as a unit on a tone arm, comprising a diaphragm, a pivoted needle arm connected to said diaphragm for operating the same, electromagnetic mechanism including a vibratory armature pivotally supported 55 independently of said diaphragm and needle arm, and means for mechanically connecting said armature to said needle arm at a point between the pivot of said arm and its connection with the diaphragm, so that 60 the vibrations of said armature at the point where it connects with the needle arm are transmitted to the diaphragm in amplified ratio.

65 3. A sound reproducer adapted to be mounted as a unit on a tone arm, comprising

ing a diaphragm, a pivoted needle arm connected to said diaphragm for operating the same, electromagnetic mechanism permanently associated with said diaphragm and including a vibratory member supported independently of said diaphragm, means for mechanically connecting said member to said needle arm, and manually operable means for rendering said connecting means inoperative to permit vibration of said diaphragm through a needle in said arm without operating said member. 70

4. In a sound reproducer adapted to be mounted as a unit on a tone arm, the combination of a diaphragm, a pivoted lever connected to said diaphragm and adapted to be operated by a phonograph needle, said connection including a holder for the needle, electromagnetic mechanism permanently associated with said diaphragm and including a vibratory member supported independently of said diaphragm and mechanically connected to said lever for operating the diaphragm independently of said needle, and means for controlling the mechanical connection between said member and said lever. 80

5. A phonograph reproducer consisting of a unitary structure having a casing, a diaphragm in said casing, a needle arm connected to said diaphragm, electromagnetic mechanism mounted in said casing and having a vibratory member mechanically connected to said needle arm, and means for controlling said mechanical connection. 85

6. In a phonograph, a tone arm provided with a phonograph sound box mounted to be swung into and out of playing position, said sound box having a diaphragm and needle arm, a telephone receiver also mounted on said tone arm and having a vibratory member adapted to be mechanically connected with said diaphragm for operating the same, and means for automatically breaking and making said mechanical connection when said sound box is swung into and out of playig position. 100

7. A sound reproducer unit contained in a substantially cylindrical casing adapted to be attached to a phonograph tone arm, said unit comprising a diaphragm, a needle arm connected to said diaphragm, a magnet mounted in said casing and having a hollow coil so arranged that its axis extends diametrically across said casing, a vibratory armature extending through said coil and supported independently of said needle arm, and means for connecting said armature to said needle arm. 115

8. In a sound reproducer, a unitary supporting frame, a diaphragm in said frame, a mechanically actuated member for operating said diaphragm, an electrically actuated member for operating said diaphragm, said members being carried by said frame independently of each other, and means for 125 130

rendering one of said members inoperative when the other member operates the diaphragm.

9. In a phonograph, a tone arm provided with a lateral extension, a curved tube swivelled laterally on said extension and carrying a reproducer, and a spring coiled about said lateral extension to counteract partially the weight of the reproducer when playing a record, said swivel mounting of the tube being independent of said spring.

10. In a phonograph, a tone arm provided with a pivotally mounted casing containing a combined phonograph reproducer and telephone receiver in which the same diaphragm is utilized for both operations, and means for automatically disconnecting the telephone receiver from the diaphragm when the casing is moved into record-playing position, said means automatically connecting the telephone receiver with the diaphragm when the casing is swung back on the tone arm into rest position.

11. A sound reproducer comprising a casing having a sound outlet, a diaphragm in said casing, a pivoted lever connected to said diaphragm for operating the same, electromagnetic mechanism in said casing, said mechanism including a vibratory armature, an operative connection between said lever and armature, means operable from outside the casing for rendering said connection inoperative, and means for operating said lever when the same is disconnected from said armature.

12. In a phonograph, a tone arm provided with a sound reproducer adapted to be swung into and out of record-playing position, said reproducer comprising a diaphragm, a pivoted lever connected to said diaphragm for operating the same, electromagnetic mechanism in said casing, said mechanism including a vibratory armature, an operative connection between said lever and said armature, means for rendering said connection inoperative, said means including an adjustable member projecting outside the casing, and a device on said tone arm for automatically engaging said member when the reproducer is swung back out of record-playing position and also when it is swung forward to play a record, said device actuating said member in one direction to break the connection between the armature and diaphragm when the reproducer is moved forward into playing position, said device also actuating said member in the reverse direction to render said connection operative when the reproducer is swung back on the tone arm.

13. In a phonograph, a tone arm provided with a sound reproducer adapted to be swung into and out of record-playing position, said reproducer comprising a dia-

phragm, a pivoted lever connected to said diaphragm for operating the same, electromagnetic mechanism in said casing, said mechanism including a vibratory armature, an operative connection between said lever and said armature, means for rendering said connection inoperative, said means including an adjustable member projecting outside the casing, and a yieldable catch device carried by said tone arm for releasably engaging said member when the reproducer is swung back out of record-playing position and also when it is swung forward to play a record, said catch device automatically pulling said member out to disconnect the armature from the diaphragm when the reproducer is moved forward into playing position and automatically pushing said member in to connect the armature with the diaphragm when the reproducer is swung back on the tone arm.

14. In a sound reproducer, a unitary structure comprising the combination of a diaphragm, connections solely mechanical for operating said diaphragm, electromagnetic mechanism permanently associated with said diaphragm for operating the same independently of said mechanical connections, said mechanism including a vibratory member adapted to be mechanically connected with said diaphragm, and means for relieving the vibratory diaphragm of the mechanical load of said member when the diaphragm is operating through said mechanical connections.

15. A sound reproducer comprising a casing, a diaphragm in said casing, means for mechanically actuating said diaphragm, means within said casing for electrically actuating said diaphragm, and mechanical means contained within said casing and operable from outside the casing for relieving the vibratory diaphragm of the load of said electric means when the diaphragm is actuated mechanically.

16. A combined phonograph-telephone reproducer adapted to be mounted on a tone arm, comprising a cylindrical casing having a sound outlet, a diaphragm supported in said casing in a plane perpendicular to the axis of the casing, a circular magnet mounted in said casing in a plane substantially parallel with said diaphragm, said magnet terminating in polar limbs extending inwardly in substantially parallel relation, pole pieces secured to said limbs and separated by an airgap, a hollow coil mounted between said polar limbs and engaging said pole pieces, whereby said coil is held firmly in position on said magnet so that the axis of the coil is practically parallel with said limbs, said magnetic airgap being in alignment with the axial opening in said coil, an armature pivoted at one

- end and extending through said coil into said airgap at the other end, whereby variable currents in said coil produce vibration of the armature in said airgap, a pivoted 5 lever connected to said diaphragm and adapted to be operated by a phonograph needle, and means for operatively connecting the free end of said armature with said lever at a point intermediate the ends thereof, whereby the vibrations of said armature are transmitted in amplified ratio to said diaphragm.
17. In a sound reproducer, a diaphragm, means for actuating said diaphragm mechanically, mechanism for operating said diaphragm electrically, means for controlling the connection between said mechanism and said diaphragm, a switch in the circuit of said electric mechanism, and means for automatically opening said switch when said mechanism is disconnected from the diaphragm, said switch being automatically closed when said mechanism is connected with the diaphragm.
18. A sound reproducer comprising a diaphragm, means for mechanically actuating said diaphragm, means for electrically actuating said diaphragm, a readily separable and restorable connection between said diaphragm and one of said means, a manually operable member for controlling said connection, and a switch for said electric means automatically controlled by said member.
19. A combined phonograph reproducer and radio loudspeaker comprising a casing, a diaphragm mounted in said casing, a needle arm for actuating said diaphragm, electromagnetic mechanism permanently mounted in said casing, said mechanism including a vibratory member supported independently of said diaphragm, a pivoted element mounted independently of said diaphragm for connecting said member to said needle arm so that the vibrations of said member are transmitted to the diaphragm by the needle arm in amplified ratio, and means operable from outside the casing for actuating said element to disconnect said member and needle arm.
20. A phonograph reproducer comprising a casing pivotally mounted on a tone arm and adapted to be thrown into and out of playing position, said reproducer having a diaphragm and a needle arm, a telephone receiver carried by said casing for operating said diaphragm, and a switch for said receiver automatically controlled by the movements of the casing into and out of playing position.
21. In a phonograph, a support mounted to turn horizontally and having a horizontal bearing portion arranged transversely thereof, a member supported in said bearing portion for vertical movement, said member being thus mounted to swing horizontally over a disk record, a reproducer carried by said member, and a spring coiled about said bearing portion for partially counteracting the combined weight of said member and reproducer when playing a record, said member being mounted on said support independently of 70 said spring.
22. A combined sound box and loudspeaking unit including a diaphragm, separate mechanical and electrical means for actuating said diaphragm, said electrical means 75 including a vibratory armature, and a controllable mechanical connection between said armature and said mechanical means.
23. In a phonograph, a tone arm carrying a reproducer arranged to be swung into and 80 out of playing position, said reproducer containing a diaphragm adapted to be operated through a phonograph needle, electromagnetic mechanism in said reproducer for operating said diaphragm, and cooperating 85 means on said tone arm and said reproducer for automatically disconnecting said mechanism from said diaphragm when the reproducer is swung into record-playing position, said cooperating means automatically restoring 90 the connection between said mechanism and said diaphragm when the reproducer is swung back out of playing position.
24. In a sound reproducer, the combination of a diaphragm, means for operating said diaphragm through a phonograph needle, electromagnetic mechanism for operating said diaphragm independently of said needle, said mechanism including a telephone 100 coil, means for disconnecting said mechanism from said diaphragm when the reproducer is operated from a record, said means being operable to restore said connection, and a switch controlled by said means for breaking the circuit through said coil when said mechanism is disconnected from said diaphragm, said switch being automatically closed when said means is operated to restore the connection between said mechanism and said diaphragm.
25. In a phonograph, a tone arm carrying a reproducer arranged to be swung into and out of playing position, said reproducer containing a diaphragm adapted to be operated through a phonograph needle, electromagnetic mechanism in said reproducer for operating said diaphragm, said mechanism including a telephone coil, cooperating means on said tone arm and said reproducer for automatically disconnecting said mechanism 115 from said diaphragm when the reproducer is swung into record-playing position, said co-operating means automatically restoring the connection between said mechanism and said diaphragm when the reproducer is 120 swung back out of playing position, and a switch controlled by said cooperating means for automatically breaking the circuit

through said coil when the reproducer is swung forward into playing position, said cooperating means automatically closing said switch when the reproducer is swung back 5 out of playing position.

26. In a phonograph, a tone arm provided with a pivoted extension, and a sound reproducer unit carried by said extension, said unit comprising a casing containing phonographic and telephonic reproducing mechanism, a switch in said casing for said telephonic mechanism, and means operable from outside the casing for controlling said switch.

27. In a phonograph, a tone arm provided with a reproducer in which a telephone receiver is permanently incorporated for actuating the diaphragm electromagnetically, said telephone receiver permitting operation 20 of the diaphragm through a phonograph needle, and spring means on said tone arm for partially counteracting the weight of said reproducer when playing a record.

28. In a phonograph, a tone arm having 25 a goose neck laterally pivoted thereon so as to swing vertically into and out of playing position, a reproducer carried by said goose neck, and a coil spring at the lateral junction of said goose neck and tone arm 30 for partially counteracting the weight of the reproducer when playing a record, said spring being so arranged as to permit the goose-neck to be thrown back on the tone arm into rest position.

29. In a phonograph, a tone arm provided with a pivoted extension, a sound reproducer carried by said extension, said reproducer containing phonographic and telephonic reproducing mechanism, a coil spring at the 40 junction of said extension and said tone arm for partially counteracting the weight of said reproducer when playing a record, and means for varying the tension of said spring to regulate its counteracting effect.

30. A sound reproducer comprising a casing, a diaphragm mounted in said casing,

a mechanically actuated member carried by said casing for operating said diaphragm, an electrically actuated member also carried by said casing for operating said diaphragm, 50 and means for rendering said electrically actuated member inactive when said mechanically actuated member operates the diaphragm.

31. A combined phonograph reproducer 55 and loudspeaking unit including a diaphragm, separate means for mechanically and electrically actuating the diaphragm, said electrical means including a vibratory member mounted independently of the dia- 60 phragm, and means for moving said member out of the vibratory path of said mechanical means.

32. A combined sound box and loud speaking unit including a diaphragm, separate 65 means for mechanically and electrically actuating the diaphragm, and a controllable switch in said unit for controlling the circuit of said electric actuating means.

33. A combined phonograph reproducer 70 and telephone receiver mounted as a unit on a tone arm and including a switch for controlling the receiver in accordance with the operative condition of said unit.

34. A combined phonograph reproducer 75 and telephone receiver mounted in a casing as a unit, a tone arm on which said casing is adjustably mounted, and a receiver circuit automatically controlled by the position of said casing on the tone arm. 80

35. In a sound reproducer, a diaphragm, means for mechanically actuating said diaphragm, means for electrically actuating said diaphragm, said electrical means including a circuit, means for controlling the connection between said diaphragm and said electrical means, a switch for said circuit, and means whereby said switch is automatically closed and opened when said connection is made and broken. 85

ADOLPH A. THOMAS.
